UNITED STATES PATENT OFFICE

2,639,950

PORTABLE TRAVELING SCAFFOLD

Claude C. Wheeler, Oxford, N. C.

Application January 4, 1950, Serial No. 136,732

7 Claims. (Cl. 304—9)

1

This invention relates to apparatus for use in the construction, repair and maintenance of highway bridges and like structures.

In the construction of steel and concrete bridges it is necessary to place and remove, from below, the forms used for laying the concrete floor. This operation has heretofore presented serious difficulties.

It is also necessary to rub and finish or re-finish concrete piers, etc., and to paint the structural steel, and the provision of equipment whereby workmen may be put in position to operate on such inaccessible parts has posed quite a difficult problem.

The general object of the present invention is, therefore, to devise apparatus by which forms or the like may be readily placed in position from the top and removed from the under side of a bridge, and by which ready access may be had to the lower surfaces of the bridge structure and to the piers for finishing, painting and repairs.

A further object of the invention is to provide apparatus of this character in the nature of a movable scaffold comprising a supporting framework on wheels adapted to travel along the upper surface of the bridge structure, and thus be positioned at any point desired in the length of the bridge, the framework of the scaffold projecting laterally beyond the edges of the bridge and having a hanger depending therefrom at each side to a point below the level of the bridge floor.

A further object is to devise a scaffold of this nature which is not only capable of traveling along a bridge, as described in the preceding paragraph, but is also portable. That is to say, the framework, and other portions of the structure are formed of parts put together with bolts and screws, and can be easily and quickly put together and taken apart, so that the apparatus may be readily moved from one job to another, and used repeatedly. This means a great saving in material, labor, time and cost.

Another object of the invention is to provide a portable, traveling scaffold of the character described comprising a framework which is laterally adjustable, so as to conform with bridge structures of different widths.

A further object is to provide a traveling scaffold of this nature equipped with derricks by means of which concrete forms and timbers may be picked up from beneath the bridge floor, or from the ground, and raised up and deposited on top of the bridge, or vice versa, as desired.

A still further object is to provide a traveling scaffold of this character in which a rigid beam

2

or supporting member, extending transversely of the bridge, beneath the floor thereof, is carried by said hangers, and may be raised and lowered as desired, to afford access to all parts of the bridge structure, including the piers.

Yet another and important object of the invention is to devise a method and means by which such rigid transverse beam or member may be shifted into a position to clear the piers when the traveling scaffold is moved along the length of the bridge.

With the above and other objects in view, and to improve generally on the details of such apparatus, the invention consists in the construction, combination and arrangement of parts herein-after described and claimed, and illustrated in the accompanying drawings, forming part of this specification, and in which:

Fig. 1 is a perspective view from beneath showing in broken lines a portion of a bridge and in full lines illustrating my improved traveling scaffold mounted thereon.

Fig. 2 is a similar view but illustrating how my improved apparatus can be used for straddling the bridge piers.

Fig. 3 is an elevation on an enlarged scale of one end of the traveling scaffold showing one of the hangers depending therefrom.

Fig. 4 is a fragmentary vertical transverse section through the apparatus shown in Fig. 3.

Fig. 5 is a fragmentary elevation showing my improved clamping means for holding the beams, the beam itself being shown in section.

Fig. 6 is a fragmentary plan view of some of the parts illustrated in Fig. 4.

Fig. 7 is a fragmentary transverse section on an enlarged scale showing the wheel guiding means which I employ.

Fig. 8 is a plan view of the framework of my improved traveling scaffold as it appears when supported on the upper surface of a bridge, parts being in section.

Fig. 9 is a side elevation of the framework shown in Fig. 8, another position of the parts being illustrated in dotted lines.

Figs. 10 and 11 are similar views, showing my improved traveling scaffold in side elevation in full lines and a portion of a bridge in transverse section in broken lines, the parts being illustrated in different positions in the two views, and

Fig. 12 is a plan view of my improved apparatus, similar to Fig. 8 but on a smaller scale, and illustrating the method of manipulating the beams or girders to enable them to be moved past the piers.

Referring to the drawings in detail, a steel and concrete bridge of conventional design is shown in broken lines as comprising a floor A, curbs B, longitudinal beams C and transverse beams D, supported on piers E.

As best shown in Figs. 8 and 9, my improved traveling scaffold comprises a framework made up of two pairs of transversely extending timbers 1 and 2 united at their ends by pairs of spaced members 3 and 4. In practice I have found it convenient to use 2" x 6" timbers for the members 1, 2 and 3, while the members 4 are preferably 4" x 6". This framework is of a length substantially equal to the width of the bridge being worked on, and in order that the framework may be adjusted to bridges of different widths, the members 1 and 2 are arranged in overlapping relation as shown in Fig. 8 and are held together by pairs of clamps 5 and 6. The members 3 and 4 are joined to the members 1 and 2 by means of angle brackets 7 and 8.

At each end of the framework above described I provide a pair of plates 9, these plates preferably lying against the inner faces of the members 1 and 2 respectively and being interposed between such faces and the ends of the members 4. The bolts which secure the brackets 7 and 8 to the members 1 and 2 pass through these plates 9 so as to rigidly unite them with the framework.

These plates 9 project a substantial distance beyond the members 4 and at each end of the framework I provide a pair of horizontal shafts or axles 10 which are welded to the outer faces of the plates 9, as clearly shown in Figs. 8 and 9. On these axles 10 are rotatably mounted pairs of wheels 11, the wheels at each end of the framework lying in the same vertical plane. These wheels are adapted to be supported and roll along either on the steel beams of the bridge frame, before the concrete is poured, or on the completed concrete curbs B of the bridge, and in order to guide them, and prevent them from slipping off the curbs, I preferably provide a trackway or guide as shown in Fig. 7. This comprises a board 38 of substantially the same width as the curb, and resting on the curb, the trackway itself being held in position by a flange 38^a engaging the edge of the curb. Secured to the upper surface of the board 38 are a pair of spaced rails 39 between which the wheels 11 freely roll.

Referring now to Figs. 3 and 4, as well as Figs. 8 and 9, I provide at each end of the framework a pair of vertical struts 12, which may conveniently be formed of angle iron, these struts being bolted or welded at their lower ends to the plates 9. A brace 13 is secured to the upper end of each strut 12 and extends diagonally to the outer end of the adjacent axle 10, where it is welded to a sleeve 14 fitting over the end of the axle. A tie bar 15 is secured to the upper end of each strut 12 and is anchored at its lower end to one of the plates 9 at a point between the members 3 and 4, as clearly shown in Figs. 4 and 8.

Supported by the pair of axles 10 at each end of the framework and depending therefrom is a hanger comprising the vertical members 16, each of which is attached to the corresponding axle by means of a connector 17, embracing the axle but free to slide thereon. The members 16 are united by a tie bar 18, both the members 16 and 18 preferably being formed of angle iron as shown. Secured to the upper end of each member 16 is a crossbar 19 provided with a series of holes 20, through any one of which may be passed a bolt uniting the crossbar 19 with the strut 12. Thus, by removing these bolts, the entire hanger may

be adjusted along the axles toward and from the wheels as desired, so as to provide the necessary clearance between the hanger and the edge of the bridge.

5 Adjacent their lower ends the members 16 are united by a tie bar 21, and are further rigidly connected by diagonally extending braces 22, as clearly shown in Fig. 3.

A bracket 23 is secured to the lower end of each member 16, so that boards 24 may be supported on these brackets and extend from one to the other thereof as shown in Figs. 1, 2 and 3, thus providing a platform on which workmen may stand.

10 Mounted upon each member 16, at a convenient height above the platform boards 24 is a winch 25, provided with a crank by which it may be turned by workmen standing on the platform. A cable 26 extends from this winch up over a pulley 27, mounted on the member 16, thence downwardly around a movable pulley 28, and thence upwardly to the upper end of the hanger where it is anchored as indicated at 29. The movable pulley 28 carries a hook 30.

15 In order to provide a support by means of which workmen may have access to the undersurface of the bridge floor and to the piers, I employ a pair of rigid beams or girders of a length substantially equal to the width of the bridge, and designated in their entirety by the numeral 31. These girders are preferably of the latticed beam type and are generally similar in construction to the booms used on large derricks. They are shown as of triangular configuration in cross section, flat on top, and are widest and deepest at their center, like a truss, tapering toward both ends, thus providing a rigid structure capable of supporting the necessary loads without appreciable bending. The girders are preferably made in two sections 20 bolted together at their middle, as indicated at 31^a. This facilitates portability, and also makes it possible to interpose between the sections a third section, if desired, to extend the length for an extra wide bridge. These beams or girders terminate at each end in a relatively small bar 32, in line with the flat top, so that when supported by these bars, the girders will not turn over. Attached to each of these bars is a clevis 33, adapted to be engaged by the hook 30, as clearly shown in Fig. 4.

25 It will now be understood that these beams or girders 31 may be suspended between cables 26 and hooks 30, and may be raised or lowered as required by means of the winches 25. When the cables are drawn up as far as possible, the bars 32 at the ends of the girders lie snugly beneath the brackets 23 as shown in Figs. 1 and 4, and these bars may be locked in this position and clamped to the hangers by the clamping device shown in detail in Fig. 5. This device consists of 30 an angular member 34 pivoted at its lower end at 35 to the member 16 and adapted to be held in the position shown in full lines by means of a turnbuckle 36 anchored to the tie bar 21 at 37. When in this position it will be seen that the member 34 snugly embraces the bar 32 at the end of the girder and locks it to the hanger. The pair of girders or beams, when thus locked at their ends to the hangers, provide a rigid structure on which any desired number of boards 24^a, extending from one girder to the other, may be supported, thus providing a platform on which workmen may stand beneath the floor of the bridge. If it is desired to space this platform further away from the bridge floor, the clamps 34 may be released and the beams or girders

lowered by means of the cables 46 and winches 25, until the desired position is reached.

In Fig. 2 I have illustrated how the pairs of beams or girders 31 may be arranged to straddle the piers E of the bridge so that by placing boards 24^a and 24^b on these girders, access may be had by workmen to all four sides of each pier. By raising or lowering the girders as required the workmen may operate on the piers throughout their entire height. Such an arrangement is particularly useful in finishing or refinishing the piers.

My improved traveling scaffold also comprises a pair of derricks mounted one at each end of the transversely extending framework. Each derrick comprises a post 40 rotatably mounted at the center of the member 4 as clearly shown in Figs. 3 and 4, and a boom 41 pivoted to the post at 42. Secured to the top of the post 40 is a plate 43, and from this plate extend a pair of diagonally disposed braces 44 attached at their lower ends to the member 3, preferably by means of the same bolts that hold the bracket 33. Thus the post 40 is rigidly supported. A chain 51 is attached at one end to the outer end of the boom 41 and extends at its other end through a keyhole slot 52 formed in a plate 53 swiveled to the top of the post 40. Thus, by taking up on this chain the inclination of the boom may be adjusted as desired.

A winch 45 is mounted on the post 40, and a cable 46 extends from this winch over a pulley 47 at the end of the boom, to and around a movable pulley 48, and is anchored at 49 to the boom. The movable pulley 48 carries a hook 50.

A plate 18^a, having a hole therein, is secured to the bar 18 at its middle, and by inserting the hook 50 of the derrick in this hole, the entire hanger may be raised and lowered as required when attaching it to or disconnecting it from the axles 10.

Referring again to Fig. 9, it will be understood that when the framework is in the position shown in full lines, it necessarily blocks the roadway over the bridge. When it is desired to open this roadway so that trucks or the like may pass through, the framework is shifted to the position indicated in dotted lines. To do this the bolts of the clamps 5 and 6 are loosened, and these clamps shifted to the left to the positions shown in dotted lines in the lower part of the figure, the clamps 5 being moved beyond the end of the members 1. This permits the members 1 and 2 to move angularly with respect to each other, the clamp 6 occupying substantially a central position and fitting loosely enough to permit the angular displacement of the members as shown. To maintain the parts in the position shown in dotted lines, the bolts of the clamp 6 may be then tightened.

It remains to describe the manner in which, by means of my improved apparatus, the girders or beams 31 may be moved around the piers as the scaffold travels along the length of the bridge.

When it is desired to move the girders past a pier, I proceed as follows. I first attach the hook 50 of one of the derrick cables 46 to the center of the girder or truss 31 to be moved, as indicated in Fig. 10. Then the clamps 34 at each end of this truss or girder are released, so that the girder is free to swing. I then take up on the boom cable 46 by winding the winch 45, while at the same time I slacken the cables 26 at the ends of the girder. This process is continued until the truss or girder has been shifted endwise into the position shown in Fig. 11 in which it is suspended by the derrick, and in which its center hangs di-

rectly below the derrick pulley. I then disconnect the hook 50 of the cable 46 from the inner end of the truss or girder, permitting this hook and cable to hang free as shown in full lines at the left of Fig. 11. This can be readily accomplished by a workman on the other truss or girder. After the cable 46 has been disconnected from the inner end of the truss or girder it is swung around into a position substantially parallel with the edge of the bridge as shown in full lines in Fig. 12. The scaffold can then be moved along the bridge as far as desired until the pier is passed. The truss or girder is then swung around into crosswise position again as indicated in dotted lines in Fig. 12 and the cable 46 from the other side of the bridge is then connected to the inner end of the truss or girder as shown in dotted lines in Fig. 11. The derrick cable is then slackened while the two winch cables 26 are progressively tightened up, and this is continued until the truss or girder goes back to its original position in which it extends transversely of the bridge. When it has been raised up into engagement with the hangers, the turnbuckle clamps 34 are again fastened around the bars 32, thus rigidly securing the truss in position. The second truss or girder may then be manipulated in the same manner.

It will thus be seen that I have provided a traveling scaffold which can be moved from one end of the bridge to the other, this scaffold comprising beams or girders extending transversely beneath the bridge, which beams or girders may be shifted to a position in which they can move past the piers, as the scaffold travels along. It will also be seen that by means of my improved arrangement of beams or girders I have provided means by which access may be had both to any part of the undersurface of the bridge structure and to all sides of the piers, throughout their entire height.

It will be understood that my novel traveling scaffold is intended to be employed in the original construction of bridges and the like, as well as in their maintenance and repair. Thus, as above mentioned, the wheels of the scaffold may be supported and roll along on the steel beams of the bridge, as soon as they are put in place, and before the concrete is poured. At this stage, the derricks may be used to advantage in hoisting and erecting or setting the forms for the concrete. Also, at this stage, the girders or trusses may be employed to afford access to the steel understructure of the bridge for painting.

After the concrete has been poured and has set, the wheels of the scaffold are supported on the floor or curbs of the bridge, as above described, and the derricks may be employed for wrecking or pulling out the forms from below the floor. These forms may either be lowered to the ground, or hoisted up on to the floor, as desired.

It will be noted that, as above pointed out, the parts of the framework of the scaffold are secured by bolts and clamps, so that they are readily separable, and can be easily and quickly taken down and put together. Also, the girders or trusses are separately fabricated units, detachable from the hangers which support them. Thus, the entire equipment may be readily disassembled, transported from one place to another, and again set up.

In conclusion, it will be seen that I have provided a novel, portable, traveling scaffold which may be used repeatedly on successive jobs for the construction, maintenance and repair of highway bridges and the like, with a tremendous sav-

ing in time, materials, labor and cost, and it is thought that the many advantages of the invention will be readily appreciated by those familiar with such matters.

What I claim is:

1. A travelling scaffold comprising a frame extending transversely across and over the deck structure of a bridge, means supporting said frame on said deck structure for longitudinal movement therealong, said frame having portions projecting outwardly beyond the lateral edges of said deck structure, a hanger fixed to and depending from each of said projecting portions to a position below the bottom of said deck structure, a pair of spaced, substantially parallel rigid beams extending between the lower ends of said hangers at a level below the bottom of said deck structure, and means for releasably and independently supporting each end of each beam from said hangers.

2. A scaffold as defined in claim 1 wherein said frame comprises slidably related pairs of elongated members extending transversely of said deck structure, the members of said pairs being relatively adjustable to vary the distance between said frame supporting means, said members being further relatively pivotally adjustable to extend inwardly and upwardly from opposite sides of said deck structure whereby to permit movement of traffic thereunder, and means for clamping said members together in said positions of adjustment.

3. A travelling scaffold comprising a frame extending transversely across and over the deck structure of a bridge, means supporting said frame on said deck structure for longitudinal movement therealong, said frame having portions projecting outwardly beyond the lateral edges of said deck structure, a hanger fixed to and depending from each of said projecting portions to a position below the bottom of said deck structure, a pair of spaced, substantially parallel rigid beams extending between the lower ends of said hangers at a level below the bottom of said deck structure, means for releasably and independently supporting each end of each beam from said hangers, each of said hangers including means at the lower ends thereof for fixedly supporting a relatively narrow platform substantially parallel to the edges of said deck structure below the level thereof and adjacent the supporting means for said beams.

4. A travelling scaffold comprising a frame extending transversely across and over the deck structure of a bridge, means supporting said frame on said deck structure for longitudinal movement therealong, said frame having portions projecting outwardly beyond the lateral edges of said deck structure, a hanger fixed to and depending from each of said projecting portions to a position below the bottom of said deck structure, a pair of spaced, substantially parallel rigid beams extending between the lower ends of said hangers at a level below the bottom of said deck structure, means for releasably and indepen-

5 ently supporting each end of each beam from said hangers, said means for supporting said beams on said hangers including means for independently raising and lowering each end of each beam relative to said hangers.

6. A travelling scaffold comprising a frame extending transversely across and over the deck structure of a bridge, means supporting said frame on said deck structure for longitudinal movement therealong, said frame having portions projecting outwardly beyond the lateral edges of said deck structure, a hanger fixed to and depending from each of said projecting portions to a position below the bottom of said deck structure, a pair of spaced, substantially parallel rigid beams extending between the lower ends of said hangers at a level below the bottom of said deck structure, means for releasably and independently supporting each end of each beam from said hangers, said means for supporting said beams on said hangers including separate latch means on said hangers arranged to engage and lock each end of each beam to said hangers in a predetermined position at said level.

7. A scaffold as defined in claim 5 wherein said latch means each comprises a member pivoted to one of said hangers and arranged to extend under and engage the outer face of an end of one beam positioned against a side of said hanger, and means for applying pressure to said member to clamp said beam end against said hanger.

8. A travelling scaffold comprising a frame extending transversely across and over the deck structure of a bridge, means supporting said frame on said deck structure for longitudinal movement therealong, said frame having portions projecting outwardly beyond the lateral edges of said deck structure, a hanger fixed to and depending from each of said projecting portions to a position below the bottom of said deck structure, a pair of spaced, substantially parallel rigid beams extending between the lower ends of said hangers at a level below the bottom of said deck structure, means for releasably and independently supporting each end of each beam from said hangers, and hoist means for separating either of said beams by its mid portion and for moving said beams endwise to position the mid portions thereof outwardly of an edge of said deck structure, said hoist means being arranged to pivotally support a beam so moved about a generally vertical axis substantially at said mid portion.

CLAUDE C. WHEELER.
